COMBINED WOODEN MIXING AND MEASURING SPOON

Robert Sidney Lutzker, Queens Village, N.Y.
(21 Lee Ave., East Williston, N.Y. 11596)

Filed July 12, 1973, Ser. No. 378,508

Term of patent 14 years

Int. Cl. D7—03

U.S. Cl. D7—50

FIG. 1

FIG. 2

FIG. 3

FIG. 4

FIG. 5

FIG. 6

FIG. 1 is a side elevational view of a combined wooden mixing and measuring spoon showing my new design;

FIG. 2 is a top plan view thereof;

FIG. 3 is a cross-sectional view taken along the line 3—3 of FIG. 2;

FIG. 4 is a cross-sectional view taken along the line 4—4 of FIG. 2;

FIGS. 5 and 6 are top plan views of modified forms of the design of FIG. 1 in which smaller measuring cavities are provided.

I claim:

The ornamental design for a combined wooden mixing and measuring spoon, substantially as shown and described.
